UNITED STATES PATENT OFFICE.

LOUIS W. STEVENS, OF BOSTON, MASSACHUSETTS.

GREASE PACKAGE.

Application filed October 27, 1924. Serial No. 746,027.

This invention relates to the merchandising of soft greases and similar lubricating compounds hereinafter, for convenience, referred to as "grease." More especially the 5 invention relates to a package of grease designed to be used in the filling of a grease gun, such packages being commonly known as "re-fill" packages.

The lubrication of many parts of a modern motor vehicle requires the use of a grease gun in which a soft grease of some kind is used. At the present time this material is usually sold in packages containing certain specified weights, the packages, however, 15 bearing no special relationship to the grease gun in which the grease is intended to be used. Consequently, when the user wishes to load a grease gun he removes the cap at one end of the gun and ladles the grease out 20 of the can or other container in which it has been sold and forces it into the gun as best he may. This is an unsatisfactory process, not only because the hands and the gun become smeared with grease, but also because 25 the forcing of the grease into the gun pockets a considerable body of air therein which prevents the complete loading of the gun.

The present invention aims to devise a re-fill grease package with the aid of which 30 a grease gun may be loaded quickly, neatly, and completely. It is also an object of the invention to devise a package of this character which can be manufactured very economically.

The nature of the invention will be 35 readily understood from the following description when read in connection with the accompanying drawings, and the novel features will be particularly pointed out in the 40 appended claim.

Referring now to the drawings,

Figure 1 is a perspective view of a package embodying the present invention;

Fig. 2 is a view, partly in cross-section, 45 and partly in elevation, showing the manner in which this package is used in filling a grease gun.

The package shown comprises a tubular shell 2, preferably made of sheet metal, and 50 of approximately cylindrical form. Near one end an internal beading 3 is formed, as by rolling, to provide an internal shoulder 4. The opposite ends of this shell are open for the entire diameter of the shell and are normally closed by caps or covers 5 and 6, respectively. Preferably the internal diameter

of the shell 2 is approximately equal to the external diameter of the barrel 7 of the grease gun, so that the end of the grease gun will fit within the shouldered end of the shell, as shown in Fig. 2, the end of the gun abutting against the shoulder 4. This container is filled with grease at the refinery, or any other convenient wholesaling plant, and it is then handled in commerce exactly 60 as are the present grease packages.

In order to fill a grease gun such as that shown at 7, Fig. 2, the screw cap on the gun should be removed and the piston 8 taken out of the barrel or cylinder. The caps 5 70 and 6 of the grease package are then removed from the shell 2 and the upper end of the grease gun is inserted in the shouldered end of the shell until it is stopped by the internal shoulder 4. The piston 8 is 75 next inserted in the opposite end of the shell and is forced down into the shell far enough to eject the grease therefrom and force it into the gun 7. It will be noted that the shoulder 4 being inwardly disposed 80 will deflect grease towards the center of the gun which is being filled and thereby prevent to a large extent any leakage at the joint between the lower end of the shell and the gun. By this arrangement the necessity 85 of threaded joints, packing and the like is avoided. It is preferable to have the discharge tube at the opposite end of the grease gun disconnected, or at least open, while this operation is being performed to permit air 90 to escape freely from the gun as it is displaced by the grease. As soon as the shell has been emptied in this manner the piston 8 is withdrawn from it, the shell is thrown away, and the piston is re-inserted in its 95 proper position in the gun 7, the usual cap being screwed in place. The gun then is ready for use.

By the use of this package the grease gun thus may be filled quickly, neatly, and completely. The nature of the package is such that its manufacture involves but a trifling expense, while being far more convenient to use than are the customary grease packages.

Having thus described my invention, what 105 I desire to claim as new is:

A refill package for grease guns comprising a shell of substantially cylindrical form filled with grease and having one end thereof open for substantially its entire diameter, a removable cover closing said end, the opposite end of said shell being slightly larger 110

in internal diameter than the grease gun with which the package is to be used, whereby the end of the grease gun may slide freely inside the latter end of the shell, a circumferential groove formed in the wall of said shell near said latter end providing an internal shoulder against which the open

end of the grease gun will abut when inserted in the shell, said shoulder serving to deflect the grease inwardly to prevent leakage between the shell and the gun during the filling operation, and a removable cover for closing the shouldered end of said shell.

LOUIS W. STEVENS.
